Primary Examiner—Doris Clark
Attorney, Agent, or Firm—Roger M. Rickert[57] **CLAIM**

The ornamental design for a plastic molded lattice assembly, as shown and described.

DESCRIPTION

FIG. 1 is a top plan view of the plastic molded lattice assembly;

FIG. 2 is a fragmentary front elevational view thereof;

FIG. 3 is a fragmentary rear elevational view thereof;

FIG. 4 is a bottom plan view thereof;

FIG. 5 is a left side elevation view thereof; and,

FIG. 6 is a right side elevation view thereof.
